UNITED STATES PATENT OFFICE.

ORLANDO M. DE HART, OF NELSON, NEBRASKA.

MAIL-CARRYING DEVICE.

1,050,008.

Specification of Letters Patent.

Patented Jan. 7, 1913.

Application filed April 23, 1912. Serial No. 692,614.

To all whom it may concern:

Be it known that I, ORLANDO M. DE HART, a citizen of the United States, residing at Nelson, in the county of Nuckolls and State 5 of Nebraska, have invented new and useful Improvements in Mail-Carrying Devices, of which the following is a specification.

This invention relates to mail carrying devices adapted for use on rural routes, the 10 object of the invention being to provide a carrying apparatus which will include a cableway leading from the house to the roadway and which will be provided with a mail container and means whereby the 15 cable can be operated to cause the container to be moved in the direction of the house on the delivery of the mail and in the direction of the road for collection of the mail.

20 In the drawings, forming a portion of this specification and in which like numerals of reference indicate similar parts in the several views:—Figure 1 is a side view of the apparatus. Fig. 2 is a top plan view thereof. Fig. 3 is a section on line 3—3 of Fig. 1. Fig. 4 is a section on line 4—4 of Fig. 1. Fig. 5 is a section on line 5—5 of Fig. 1.

In carrying out the invention I preferably provide the endless cableway 1, the 30 ends of the cable being looped around the idle pulley 2 and the driving pulley 3, the latter being mounted on the supporting post 4 which is disposed adjacent to the roadway. The idle pulley 2 is mounted on a post 5 which may be located in close proximity to the house or station to which the mail is to 35 be delivered by the postman. The pulley wheel 3 is provided with a rim 6 in which is formed a V-groove 7 for the cable. This 40 groove is partly embraced by a combined concavo-convexed cable guide and stop member 8. The member 8 is secured in any suitable well known manner to the post 4 and it is bent upon itself to provide upper and 45 lower portions 9 and 10 through which the upper and lower portions of the cable are adapted to pass, the said portions partially embracing the opposite side edges of the peripheral portion of the pulley thereby 50 keeping the said pulley true and preventing any wobbling motion during its rotation.

The shaft 11 of the pulley wheel 3 has fixed thereto a relatively small gear wheel 12 which is arranged in intermeshing en-

gagement with the large driving gear wheel 55 13. The wheel 13 is operatively supported on the post 14 and is provided with a suitable crank handle 15. The intermediate posts 16 for supporting the cable are provided with brackets 17 on which are mounted 60 the lower superimposed rollers 18 and 19 between which the cable is adapted to travel, the upper rollers 19 being yieldable so as to permit of the passage of the box clamp 20 therethrough. The box clamp supports a 65 mail box 21 which may be of any suitable well known construction, the same being preferably provided at one end with a door 22 and in some conspicuous place the box is provided with a signal flag 23. The pulley 70 2 is partly embraced by a combined cable guide and stop member 24, the same having thereon the superimposed portions 25 and 26 for receiving the superimposed portions of the cable. The portion 10 of 75 the cable guide 8 and the portion 26 of the cable guide 24 are disposed in the path of movement of the box clamp 20 so as to engage the same to limit the movement of the box in two directions, thereby positively 80 preventing movement of the box over the driving and idle pulleys respectively.

In use, the postman desiring to deliver mail to the house places the same in the box 21, after which the driving gear wheel 13 85 is actuated so that the box will be propelled in the direction of the idle pulley 2. After the mail has been delivered as just described, the box may remain at its receiving station so as to be used when it is desired to place 90 mail in the same for collection.

I claim:—

In a mail carrying device, an endless cable supporting pulleys therefor, a receptacle secured to the cable, means disposed in 95 the path of the receptacle for preventing movement of the same over the supporting pulleys, said means consisting of a concavo-convexed member embracing the opposite peripheral edges of the pulley thereby preventing any lateral movements of the pulley 100 during its rotation.

In testimony whereof I affix my signature in presence of two witnesses.

ORLANDO M. DE HART.
